[57] CLAIM

The ornamental design for a circular baby crib, as shown and described.

DESCRIPTION

FIG. 1 is a frontal perspective view of a circular baby crib according to my new design, the rear of the design being similar;

FIG. 2 is a side perspective view showing my new design, the opposite side being similar;

FIG. 3 is a perspective view from a position showing the front and side of my new design;

FIG. 4 is a perspective view from inside the circular baby crib, looking outward toward the front, the view of the design in the opposite direction being similar;

FIG. 5 is a top plan view showing my new design; and,

FIG. 6 is a top plan view, in perspective, showing my new design.
